CLAIM

I claim the ornamental design for a mount, as shown and described.

DESCRIPTION

FIG. 1 is a front perspective view of a mount in accordance with an embodiment of my new design for displaying the artwork of an item while the item is positioned on the mount; FIG. 2 is a rear perspective view of the mount of FIG. 1; FIG. 3 is a front elevation view of the mount of FIGS. 1-2; FIG. 4 is a rear elevation view of the mount of FIGS. 1-3; FIG. 5 is a top view of the mount of FIGS. 1-4; FIG. 6 is a bottom view of the mount of FIGS. 1-5; FIG. 7 is a left side elevation view of the mount of FIGS. 1-6; and,

FIG. 8 is a right side elevation view of the mount of FIGS. 1-7.

The broken lines shown in the figures represent portions of the suction mount that form no part of the claimed design. The broken line showing immediately adjacent to the shaded areas represents boundaries to the claimed design and forms no part of the claimed design.

The broken away symbols in the drawings indicate that any portion of the article beyond what is shown forms no part of the claimed design.
